FEMALE URINAL

Hattie Deslauriers, nee Robillard, 1939 David St.,
Duvernay, Quebec, Canada
Filed Mar. 5, 1964, Ser. No. 349,720
1 Claim. (Cl. 4—110)

The present invention relates to a urinal for women, more particularly adapted for use by bed-ridden women.

In order to enable a bed-ridden woman to urinate in a conventional pan-like urinal, the nurse must lift the patient for insertion of the urinal in proper position. This requires considerable effort on the nurse's part, especially when the patient is impotent and/or obese. Moreover, the nurse must forego more important occupations to provide this help to the woman-patient.

The general object of the present invention resides, therefore, in the provision of a female urinal which obviates the above-noted disadvantages and, more particularly, enables a bed-ridden woman to use the urinal herself without any help and without having to raise herself.

Another object of the present invention resides in the provision of a urinal of the character described, which is provided with a handle for ease in the handling of the urinal to place it in proper position and which also serves to suspend the urinal in an accessible place, when not in use, such as the side of the bed.

Another object of the present invention resides in the provision of a urinal of the character described, which is of relatively simple and inexpensive construction and which provides the assurance that all of the urine will enter the vessel and not spill and soil or dampen the bed sheets.

The foregoing and other important objects of the present invention will become more apparent during the following disclosure and by referring to the drawings, in which:

FIGURE 1 is a perspective view of the urinal in accordance with the present invention;

FIGURE 2 is a top plan view;

FIGURE 3 is a front elevation; and

FIGURE 4 is a side elevation.

Referring now more particularly to the drawings in which like reference characters indicate like elements throughout, the urinal in accordance with the invention can be made of glass, plastic material, but preferably of enameled metal, in order to be unbreakable and to facilitate sterilizing thereof.

The urinal consists of a generally tubular elongated vessel, but having a substantially oval plane cross-section whereby the vessel defines lateral walls 1, a front wall 2, and a back wall 3, said walls being joined at one end by a flat bottom 4. The upper portion of the vessel is provided with an opening or mouth 5 lying in an inclined plane relative to the long axis of the vessel whereby said mouth is inclined downwardly and forwardly with respect to the vessel.

The upper edge portion 6 of mouth 5 is disposed approximately in the central transverse plane of the vessel, as seen in FIGURE 2, and is slightly concave. This edge portion 6 is formed by the marginal part of a curved convex top wall portion 7 which forms an extension of lateral walls 1 and of back wall 3.

The lateral edge portions 8 of mouth 5 are concave and are joined at front wall 2 by a substantially straight

2

edge portion 9 substantially parallel to bottom 4. A handle 10 in the form of a hook is rigidly secured to the top wall 7 and protrudes from the top and back of the vessel. The contour of mouth 5 is preferably provided with a bead 11 of rounded cross-section.

The urinal in accordance with the invention is used in the following manner:

The female patient, who is lying on her back, places the urinal in upright position between her two legs such that the bead 11 of mouth 5 will encircle the vaginal lips and bear firmly against the skin.

The vessel is maintained in position by means of handle 10 and/or by the top 7. The contour of mouth 5 conforms to the vaginal lips and makes a substantial liquid-proof contact therewith, whereby urine cannot spill over. Because the vessel has an oval plane cross-section, it can be inserted in position without requiring the patient to spread her legs excessively apart.

Because front wall 2 is substantially vertical when the vessel is in its position of use, no portion of the vessel protrudes underneath the seat of the user and, therefore, the latter does not have to lift or raise herself in any way and does not, therefore, require any help.

The vessel can rest in stable upright position on its flat bottom wall 4. The vessel is easy to clean and sterilize and is of inexpensive construction. If desired, the shape of the urinal can be modified; for instance, by elongating its oval-shaped cross-section towards the front of the vessel in order to increase its content and/or by decreasing its height to accommodate women of different ages.

While a preferred embodiment in accordance with the present invention has been illustrated and described, it is understood that various modifications may be resorted to without departing from the spirit and scope of the appended claim.

What I claim is:

A female urinal comprising an elongated vessel having at one end a flat bottom whereby the vessel can be positioned in upright stable position, a curved wall defining the front, the back and the sides of said vessel and having a substantially oval-shaped plane cross-section, a top wall merging with the back and sides of said wall, said vessel being provided with a mouth defined by the upper edge of the front and sides of said curved wall and by said top wall, the lateral edge portions of said mouth being concave, said mouth lying in a plane which is inclined towards the bottom and front of said vessel with respect to the long axis of said vessel, the front edge portion of said mouth being straight and substantially parallel to said bottom wall and in substantial alignment with the front of said curved wall.
